DESIGN FOR A CASSEROLE

Berthold Moser-Benedikt, Karlsbad, Czechoslovakia, assignor to R. H. Macy & Co., Inc., New York, N. Y., a corporation of New York

Application December 31, 1935, Serial No. 60,367

Term of patent 14 years

To all whom it may concern:

Be it known that I, Berthold Moser-Benedikt, a citizen of Czechoslovakia, residing at Eduard Knollstrasse, Karlsbad, Czechoslovakia, have invented a new, original, and ornamental Design for a Casserole, of which the following is a specification, reference being had to the accompanying drawing, forming part thereof.

I claim:

The ornamental design for a casserole, as shown.

BERTHOLD MOSER-BENEDIKT.
